(57) **CLAIM**

The ornamental design for a cake pan having removable spatula, as shown and described.

DESCRIPTION

FIG. 1 is a front, left, top perspective view of a cake pan having removable spatula showing my new design;

FIG. 2 is a left side view thereof;

FIG. 3 is a right side view thereof;

FIG. 4 is a rear view thereof;

FIG. 5 is a front view thereof;

FIG. 6 is a top view thereof; and,

FIG. 7 is a bottom view thereof.

The portions in the drawings illustrated in broken lines represent the environment of the design and therefore form no part of the claimed design.
